(57) **CLAIM**

The ornamental design for a paint mixing paddle, as shown and described.

DESCRIPTION

FIG. 1 is a front and right side perspective view of a paint mixing paddle showing a first embodiment of my new design;

FIG. 2 is a front view thereof, the rear view being a mirror image;

FIG. 3 is a right side view thereof;

FIG. 4 is a left side view thereof;

FIG. 5 is an end view thereof, the other end view being a mirror image;

FIG. 6 is a front view of another paint mixing paddle showing a second embodiment of my new design;

FIG. 7 is a left side view of the second embodiment of my new design; and,

FIG. 8 is a right side view of the second embodiment of my new design.

The end view of the second embodiment of my new design is the same as the illustration in FIG. 5.
